UNITED STATES PATENT OFFICE.

WILLIAM SEVILLE, OF HOPEDALE, MASSACHUSETTS, ASSIGNOR TO DRAPER CORPORATION, OF HOPEDALE, MASSACHUSETTS, A CORPORATION OF MAINE.

STARTING AND STOPPING MECHANISM FOR LOOMS.

Application filed February 7, 1927. Serial No. 166,281.

This invention relates to improvements in the construction and operation of means for starting and stopping a loom.

A loom is usually provided with a shipper, by means of which the power may be thrown on and off, as by shifting a belt from a loose to a fast pulley and vice versa, or as by connecting and disconnecting a clutch, and is also usually provided with a suitable brake, an actuator for the brake and a controller by which the brake may either be applied or released, the brake usually being applied coincidentally with the throwing off of the power and released when the power is on.

A familiar type of such mechanism is disclosed in the patent to Ambler, No. 867,934, granted October 8, 1907, and, while the present invention is in its broader aspects of wider application, it is more particularly for the purpose of improving the construction and operation of this general type of mechanism and for securing advantages and results not hitherto obtainable.

In the operation of a loom, it is desirable that the brake be releasable independently of the operation of the shipper because it is frequently necessary either to turn the loom over by hand or to allow the power to be thrown on a little at a time. This is necessary in piecing the goods, matching the pick, properly positioning the shuttle and otherwise adjusting the operation of the loom.

Various means are also commonly employed for stopping the loom. If the shuttle is improperly boxed a protector mechanism is commonly employed acting through a frog. If a warp breaks, a warp stop motion acts through suitable connections. If the filling breaks or becomes exhausted, a weft fork may act through suitable connections. So also it is desirable to stop the loom by hand from different positions with respect to the loom. In such and other cases it is obviously desirable that the shipper shall throw off the power and the brake shall be applied at the same time. So also, in starting the loom, the brake must be released simultaneously with or in advance of the throwing on of the power.

Again, whether the operation of stopping and starting the loom is controlled by hand or automatically, it is of importance that

the operation shall be positive, certain and under the control of a minimum exertion of force.

It is the object of the present invention to provide for all these and other requirements by a simple and efficient principle of construction.

It is the object of the invention further to provide a construction having a principle of operation which permits of such leverage ratios as to permit the operations of starting and stopping to be effected by the application of small amounts of force, either by hand or automatically.

It is also desirable that the loom when stopped shall stop at or near some definite point in its cycle of movement and it is a further object of the invention to provide a mechanism acting to secure this result.

The break actuator is commonly operated or moved to its brake applying position by a spring and a further object of the present invention is to employ the impulse of this spring to accelerate the movement of the brake controller to applying position and consequently to assist in a prompt and definite application of the brake.

Another feature of the invention resides in the employment of a latching mechanism by means of which the brake actuator is held against the power of its spring, locked in releasing position, and which, by the application of a comparatively small force exerted in the movement of the controller from releasing to applying position, is unlocked.

These and other objects and features of the invention will appear more fully from the accompanying description and drawings and will be particularly set forth in the claims.

As the general construction and operation of a loom, of the usual means for connecting and disconnecting power to and from the main shaft, of the various mechanisms employed for automatically initiating the stopping of the loom upon the mispositioning of the shuttle, the breakage or failure of a warp or filling, of the usual brake mechanism and of other features are well known and familiar to those skilled in the art, it is only necessary for the purposes of this invention here to illustrate and describe those features of construction with which the invention is more particularly concerned.

In the drawings:

Fig. 1 is a side elevation of a portion of a loom of an ordinary type with a preferred form of construction embodying the present invention embodied therein.

Fig. 2 is a front elevation of the loom partially broken away.

Fig. 3 is a top plan view on a larger scale of the shipper and controller mechanism shown in Figs. 1 and 2.

Fig. 4 is a detail in side elevation and partially broken away of the construction shown in Fig. 3 with the controller and actuator in applying position.

Fig. 5 is a detail in cross section taken on the line 5—5 of Fig. 4.

Fig. 6 is a detail in cross section taken on the line 6—6 of Fig. 4.

Fig. 7 is a detail in cross section taken on the line 7—7 of Fig. 3.

So much of the loom as is illustrated is of the well known automatic Northrop type having the side frames 1 and 2, the connecting breast beam 3, the hopper stand 4 carrying the magazine or hopper 5 and having the main shaft 6 driven from a suitable source of power which may be of any usual form and is not illustrated.

A bracket 7 is secured to the loom side 1 and is provided with the depending flange 8. A stud is rigidly mounted in and projects from the flange 8. This stud preferably presents a central, polygonal section 9 and cylindrical threaded ends 10 and 11. The central section 9 enters a correspondingly shaped aperture in the flange 8, as shown in Fig. 7, and a nut 12 is threaded on the end 10 and abuts the flange 8. A bearing sleeve 13 having a bore shaped to conform to the section 9 of the stud is mounted thereon and provided with a flange 14 at its inner end which abuts the flange 8, while its outer end projects beyond the section 9 of the stud and is provided at its outer face with a recess.

An abutment member 15, the function of which will later be described, fits over the cylindrical end 11 of the stud and is provided with a projection 16 fitting the recess in the end of the sleeve 13. A nut 17 is threaded on to the end 11 of the stud. It will thus be seen that when the nuts 17 and 12 are tightened up, the stud is held rigidly in the flange 8, and the abutment member 15 is held rigidly in a fixed position with the bearing section of the sleeve extending from the inner wall of the abutment member to the head 14 of the sleeve.

The shipper 18 is in the form of a lever having a hub 19 journalled on the bearing section of the sleeve 13. The controller 20 is also in the form of a lever having a hub 21 also journalled on the bearing section of the sleeve 13. The hubs 19 and 21 are slightly less in total thickness than the length of the bearing portion of the sleeve

so that both the shipper and the controller swing freely and easily on the bearing sleeve.

The upper and longer arm 22 of the shipper terminates in a handle by which it may readily be operated, while the lower and shorter arm 23 is provided at its end with an aperture 24 from which a connection may extend to any suitable means for throwing on and off the power, it being understood that when the shipper is in the position shown in Figs. 1, 2 and 3, the power is on, and when it is swung to the opposite position or to the left, viewing Fig. 1, the power is off.

The brake mechanism illustrated is shown as a brake wheel 25 keyed to the main shaft 6 and a cooperating brake band 26 pivotally secured at one end 27 to the loom frame and at the other end at 28 to a link 29 pivoted at 30 to an upwardly extending arm 31 of a bell crank lever fulcrumed at 32 to the loom frame. The other arm 33 of the bell crank lever extends substantially horizontally to a point beneath and to the rear of the fulcrum stud of the controller and shipper. A longitudinally adjustable link comprising the bar 34 threaded into the lower end of the flat plate 35 is pivoted at its lower end to the free end of the arm 33 and extends vertically upward therefrom past and to the rear of the fulcrum of the shipper and controller. An actuating spring 36 herein shown as of the tension type is secured at its upper end to the arm 33 and at its lower end to some fixed part of the loom. It will be seen that the spring acts through the bell crank lever 31, 33 and the brake band to apply the brake, and that an upward pull on the link 34, 35 acts to release the brake. The bell crank lever 31, 33 with its operating spring 36 and the lever 34, 35 therefore constitute a brake actuator.

A latch 37 is pivoted at its upper end at 38 to the upper end of the plate 35 of the link and is provided at its lower front end with a notch or recess 39 adapted to engage a small antifriction roller 40 journalled at 41 in the rear end of the abutment member 15 already described. A helical spring 42 seated in a recess in the outer face of the link plate 35 engages a stud 43 secured to and projecting inwardly from the latch 37 and acts to swing the latch forwardly or toward the abutment. The construction is such that when the actuator is moved to releasing position by an upward pull on the link 34, 35 in opposition to the spring 36 and the notch 39 comes opposite the roller 40, the latch will swing forwardly into engagement with this roller on the abutment and thus lock the actuator and brake in released position. It will be seen that in this position no strain is placed upon the controller or shipper to hold the brake released

against the tension of the spring 36. It will also be seen that in order to apply the brake and allow the actuating spring 36 to act with full force, all that it is necessary to do 5 is to knock the latch off the abutment.

The construction, including this latching mechanism, is so arranged that only a small amount of force is required, due to the principle of leverage ratios employed, to place 10 the parts in locked position and only a small force is required to unlock the latch and permit the application of the brake. In the preferred construction illustrated, both of these things, that is, the raising of the latch 15 to locking position and the unlocking of the latch, are done through direct connections with the brake controller 20. To enable the link 34, 35 carrying the latch to be raised, an arm 44 is extended rearwardly from the 20 controller 20 and is provided at its rear end with an arcuate slot 45 in the bottom of which is an adjustable screw locked with a check nut and engaging a pin 46 secured to and projecting inwardly from the link plate 25 35. To knock off the latch 37 from the abutment 15, when in locked position, a knock-off link is employed connecting the controller and the latch. This knock-off link is shown as an adjustable two-part device 30 comprising a bar 47 slotted at 48 at its rear end to engage a pin 49 secured in the link 37 near its lower end and having at its forward end a hub 50 through which passes a threaded L-shaped rod 51, carrying check 35 nuts 52 by which it is adjusted in the hub 50 and which at its forward end is journaled in a sleeve 53 rigid with and projecting laterally from the controller 20 above its fulcrum. The slot 45 permits limited, 40 relative movement longitudinally of the actuator link between the controller arm 44 and the pin 46 and thus enables the controller 20 to be swung sufficiently from releasing position to knock the latch off the abutment. Immediately, however, the latch is 45 knocked from the abutment, the pin 46 will engage the lower end of the slot and the impulse of the actuator spring 36 will accelerate the latter portion of the movement of the controller to applying position. The 50 slot 48 in the knock-off link permits the necessary swinging movement of the latch 37 to ride upward past the roller 40 and then into locking position when the link 34, 55 35 is raised and the latch 37 is provided at the front with a suitable cam face 54 for this purpose.

Suitable means interposed between the shipper and controller so arranged that when both 60 the shipper and controller are in the same position and the shipper is swung in either direction, the controller will swing with the shipper, and so arranged when the shipper is in "on" position and the controller in releasing position and the controller is then

swung to applying position, the shipper will swing to "off" position, and so arranged that when the shipper is in "off" position and the controller is in applying position and the controller is then swung to releasing position 70 as to permit the shipper to be swung independently between "off" and "on" positions. In the construction illustrated, the controller 75 20 at its lower end is provided with an arm 55 extending below its fulcrum which has a projection 56 extending laterally behind the head of a screw stud 57 adjustably mounted in the lower end of the shipper. At a point well above the fulcrum the shipper has pivotally mounted thereon a latch 58, the head 80 of which is adapted to slide over and engage the front face of a lug 59 projecting laterally from the controller, while the tail 60 of this latch, when the shipper reaches releasing position, engages a buffer 61 on the 85 flange 8 and releases and holds released the latch from the lug 59.

The usual frog mechanism, not shown, will preferably act against the rear face of the arm 55 and the warp stop, filling fork, 90 or other mechanisms employed, may be connected as usual at suitable points.

When the loom is to be stopped manually from the left hand side, the shipper handle 18 is to be employed. When the loom is to 95 be stopped from the right hand side, a mechanism such as that illustrated may be employed. A shaft 62 is mounted in suitable bearings 63 on the loom frame and extends transversely thereof. At the left-hand side 100 this shaft is provided with a depending arm 64 having a projection 65 extending in front of the shipper and a projection 66 extending behind a lug 67 on the shipper. At the right-hand side, the shaft 62 is provided 105 with an upwardly extending arm 68 connected by a link 69 to a lever 70 fulcrumed on a stud 71 mounted in a suitable bracket 72, in this case shown as carried by the hopper stand 4. It will thus be seen that by 110 moving the lever 70 at the right-hand side of the loom in one direction or the other, the shipper will be moved in the same direction and consequently the same occurrences will take place whether the operative grasps the 115 handle on the lever 70 or the handle on the shipper 18.

The principle of inter-engaging means on the controller 20 and the brake actuator which act, when the controller is swung to releasing position, to move the brake actuator to release the brake and permit the latch to engage the abutment, together with the means on the controller which knocks the latch off the abutment when the controller is 120 swung from releasing position and permits the actuator to apply the brake, enables leverage ratios to be employed permitting the application of a relatively small force either to the lever 70 at the right-hand side of the 125 130

loom or to the shipper 18 at the left-hand side of the loom to effect the starting and stopping of the loom.

So also the principle of the knock-off release of the latch, together with the acceleration of movement of the controller to brake applying position under the impulse of the brake actuator spring, enables the loom to be stopped at a fairly definite point in its 10 cycle of movement and in a positive and certain manner.

The connections provided also enable the brake to be released independently of the 15 operation of the shipper, thus enabling the operative to turn the loom over by hand or to throw the power on a little at a time, as may be required.

The connections also enable the parts to be timed so that, when the loom is to be 20 stopped, the application of the brake may begin before the power is thrown off, thus ensuring a still more accurate stopping of the loom at a predetermined point in its cycle of movement.

25 The invention thus presents a simple, effective, efficient and accurately and easily controlled stopping and starting mechanism for a loom.

Having thus described the invention, 30 what is claimed as new and desired to be secured by Letters Patent is:

1. Starting and stopping mechanism for a loom comprising a shipper for throwing the power on and off, a brake, a spring-operated actuator therefor, a controller for the actuator, the said shipper and controller being pivoted side by side upon a common axis, a fixed abutment, a latch movably mounted on the brake actuator and engageable with the abutment when the brake is released to lock the actuator and brake in released position, means acting, when the controller is swung to releasing position, to move the actuator against its spring and allow the latch to engage the abutment and, when the controller is swung to applying position, to knock the latch off the abutment and allow the actuator to apply the brake, and means interposed between the shipper and controller acting, when both are in the same position and the shipper is swung in either direction, to swing the controller with the shipper and, when the shipper is in "on" position and the controller in releasing position and the controller is swung to applying position, to swing the shipper to "off" position, and, when the shipper is in "off" position and the controller in applying position and the controller is swung to releasing position, to permit the shipper to be swung independently between the "off" and "on" positions.

2. Stopping mechanism for a loom comprising a brake, a spring-operated actuator therefor, a pivotally mounted controller for

the actuator, a fixed abutment, a latch movably mounted on the actuator and engageable with the abutment when the brake is released to lock the actuator and brake in released position, and means acting, when the controller is swung to releasing position, to move the actuator against its spring and allow the latch to engage the abutment, and, when the controller is swung to applying position, to knock the latch off the abutment and allow the actuator to apply the brake. 70 75

3. Starting and stopping mechanism for a loom comprising a shipper for throwing the power on and off, a brake, a spring-operated actuator therefor, a controller for the actuator, the said shipper and controller being mounted to move together from "on" to "off" position and from releasing to applying position, respectively, latching mechanism acting to lock the actuator and brake in released position, and means acting, when the controller is swung from releasing to applying position, to unlock the latching mechanism and allow the actuator to apply the brake. 80 85 90

4. Starting and stopping mechanism for a loom comprising the construction defined in claim 3 in which, when the latching mechanism is unlocked, the impulse of the actuator spring acts to accelerate the movement of the controller and shipper to applying and "off" positions respectively. 95

5. Starting and stopping mechanism for a loom comprising a shipper for throwing the power on and off, a brake, a spring-operated actuator therefor, a controller for the actuator, the said shipper and controller being mounted to move together from "on" to "off" position and from releasing to applying position, respectively, a fixed abutment, a latch movably mounted on the actuator and engageable with the abutment when the brake is released to lock the actuator and brake in released position, and means acting, when the controller is moved to releasing position, to move the actuator against its spring and allow the latch to engage the abutment, and, when the controller is moved to applying position, to knock the latch off the abutment and allow the actuator to apply the brake. 100 105 110 115

6. Starting and stopping mechanism for a loom comprising a shipper for throwing the power on and off, a brake, a spring-operated actuator therefor, a controller for the actuator, the said shipper and controller being mounted to move together from "on" to "off" position and from releasing to applying position, respectively, a fixed abutment, a latch movably mounted on the actuator and engageable with the abutment when the brake is released to lock the actuator and brake in released position, and means acting, when the controller is moved to applying position, to knock the latch off the abutment and allow the actuator to apply the brake. 120 125 130

the abutment and allow the actuator to apply the brake.

7. Stopping mechanism for a loom comprising a brake, a fixed abutment, a pivotally mounted controller, a spring-operated brake actuator having a link extending past the abutment and at one side the controller pivot, a latch movably mounted on the actuator link and moved, when the actuator link is moved in opposition to the actuator spring, into locking engagement with the abutment, an arm extended from the controller and engaging the actuator link with a connection permitting limited, relative movement longitudinally of the actuator link and a knock-off link connecting the controller and latch, whereby when the controller is swung to applying position, the knock-off link first knocks the latch off the abutment and then the impulse of the actuator spring acts to accelerate the movement of the controller to applying position.

8. Stopping mechanism for a loom comprising a brake, a spring-operated actuator therefor, a pivotally mounted controller for the actuator, a fixed abutment, a latch movably mounted on the actuator and normally movable into locking engagement with the abutment, inter-engaging means on the controller and actuator acting, when the controller is swung to releasing position, to move the actuator to release the brake and permit the latch to engage the abutment, and means on the controller to knock the latch off the abutment, when the controller is swung from releasing position, and permit the actuator to apply the brake.

9. Starting and stopping mechanism for a loom comprising the construction defined in claim 8, together with a shipper pivotally mounted on the same axis with the controller for throwing the power on and off, and means interposed between the shipper and controller acting, when both are in the same position and the shipper is swung in either direction, to swing the controller with the shipper, and, when the shipper is in "on" position and the controller in releasing position and the controller is swung to applying position, to swing the shipper to "off" position, and, when the shipper is in "off" position and the controller in applying position and the controller is swung to releasing position, to permit the shipper to be swung independently between "off" and "on" positions.

10. Starting and stopping mechanism for a loom comprising the construction defined in claim 3 in which a latch connects the said shipper and controller when in "on" and releasing position, respectively, and causes them to move together as specified in said claim and in which means are provided for releasing, and holding released, the latch when the shipper is in "off" position.

11. Starting and stopping mechanism for a loom comprising the construction defined in claim 8, together with a shipper pivotally mounted on the same axis with the controller for throwing the power on and off, a latch connecting the shipper and controller when in "on" and releasing position, respectively, and means acting to release, and to hold released, the said latch when the shipper is in "off" position.

12. Starting and stopping mechanism for a loom comprising the construction defined in claim 3, together with a hand operated lever mounted at the side of the loom opposite the shipper and connections therefrom to the shipper to effect the simultaneous movements thereof in the same directions.

13. Starting and stopping mechanism for a loom comprising the construction defined in claim 5, together with a hand operated lever mounted at the side of the loom opposite the shipper and connections therefrom to the shipper to effect the simultaneous movements thereof in the same directions.

14. Starting and stopping mechanism for a loom comprising the construction defined in claim 6, together with a hand operated lever mounted at the side of the loom opposite the shipper and connections therefrom to the shipper to effect the simultaneous movements thereof in the same directions.

15. Stopping mechanism for a loom comprising a brake, a spring operated actuator therefor, a pivotally mounted controller for the actuator, an arm on the controller extending laterally of its pivot, a link on the actuator connected to said arm and extending substantially tangent to the arc of movement of said arm thus to produce a highly efficient leverage in transmitting the releasing movement of the controller to the actuator.

In testimony whereof, I have signed my name to this specification.

WILLIAM SEVILLE.
